W. M. WALKER.

REAMER DRILL FOR WELL BORING.

APPLICATION FILED FEB. 5, 1917.

1,278,402.

Patented Sept. 10, 1918.

W. M. Walker,

John M. Spellman
ATTORNEY.

UNITED STATES PATENT OFFICE.

WILLIAM M. WALKER, OF FRISCO, TEXAS.

REAMER-DRILL FOR WELL-BORING.

1,278,402.

Specification of Letters Patent. Patented Sept. 10, 1918.

Application filed February 5, 1917. Serial No. 146,691.

To all whom it may concern:

Be it known that I, WILLIAM M. WALKER, a citizen of the United States, residing at Frisco, in the county of Collin and State of 5 Texas, have invented certain new and useful Improvements in Reamer-Drills for Well-Boring, of which the following is a specification.

My invention has relation to an improvement 10 in reamer drills for boring wells or the like and in such connection it relates more particularly to the construction and arrangement of the drill.

Heretofore in the drilling of wells, the 15 drill surrounded by and in advance of the casing of the well was usually provided with reaming projections or arms which as the drill advanced in the earth or rock would enlarge the hole sufficiently to permit 20 the casing with its couplings to descend in the hole, the drill itself not being adapted to drill a hole of sufficient diameter to accommodate the couplings. In such combined drill and reamer, a rather complicated 25 toggle construction was required to permit of the reamer arms to be drawn or folded inward to permit of the drill being withdrawn through the casing.

Some attempts have also been made to 30 form a drill which as it is projected below the casing may expand to drill a hole and ream it out to the required diameters. Such structures, however, have not been successful for several reasons among which are the 35 following:

In the drill there was no provision of a 40 groove or channel between the wings or forks of the drill proper for the purpose of permitting the mud, etc., escaping upward in the casing and in such drill there was no provision for limiting the expansion or separation of the forks of the drill which would occur if the drill struck rock or hard surfaces during the drilling operation.

45 My present invention contemplates the provision of a drill which may expand as it leaves the casing to form a drill and reamer, said expanding drill having between its diverging forks a groove or channel into which the mud may pass during the drilling operation and which drill also is provided with means for limiting the ex-

pansion or separation of the forks as the drill advances through the rock or hard strata.

55 The nature and scope of my invention will be more fully understood from the following description taken in connection with the accompanying drawings forming part hereof, in which—

Figure 1, is a side elevational view of a 60 drill and reamer embodying my invention, the surrounding casing being shown in section, and the drill projecting beyond the lower end of said casing.

Fig. 2, is a vertical sectional view of the 65 drill when drawn upward in the casing, the plane of said section being taken on line 2—2 of Fig. 3.

Fig. 3 is a view similar to Fig. 1 but illustrating the drill drawn up into the casing.

Fig. 4 is an end elevational view of Fig. 3.

Fig. 5 is a cross-sectional view taken on the line 5—5, of Fig. 1, and

Fig. 6 is a cross-sectional view taken on 75 the line 6—6 of Fig. 3.

Referring to the drawings 1 represents the casing which is in sections united together by couplings 2 screwed on the exterior of meeting ends of sections 1. Within 80 the casing 1 the drill is adapted to be lowered, said drill having a screw or other connecting upper end 3 fitting into a sectional drill rod not shown.

The main body 4 of the drill is formed of 85 tool steel or similar spring metal and its lower or drilling end is divided into two forks 5. These forks 5 each have a main body portion 6 which is flattened the body portions of the respective forks being contiguous to and riding over each other. The width of each flat body portion 6 is slightly less than the diameter of the inclosing casing 1, so that when both forks are drawn 90 upward in the casing the flat body of one fork lies upon and coincides in extent with the flat body of the other fork as clearly shown in Fig. 4. When however the drill projects beyond the casing the two forks

95 spring apart and the flat bodies 6 slide over each other to make a body which is of larger diameter than either the casing 1 or the coupling 2 as clearly shown in Figs. 1 and 5.

100 Each drill fork 5 has its flat body pro-

vided at either end with a curved cutting flange 7 and 8 respectively and between these flanges a groove 9 is formed into and through which the mud or earth or rock 5 may pass upward as the drill advances. This groove 9 of each fork 5 is what is termed a mud groove and both grooves 9 terminate at their upper ends in the recess 10 cut into the drill body 4 to form the forks 5 of the drill. This drill body 4 is slightly flattened (see Fig. 2) on two faces to form a continuation of the space or channel through which the mud or excavated matter may pass upward into the casing. 15 To prevent accidental spreading of the drill forks during drilling the inner flanges 8 will serve in a measure to hold the drill to its work. In addition to these flanges 8 a positive means for preventing the too 20 wide separation of the forks of the drill is provided. This means consists preferably of one or more pins 11 secured to one flat body 6 of the drill and working in one or more slots 12 formed in the other flat 25 body 6. It has been found that two pins and two slots arranged as shown in the drawings will be preferable in securing the two drill forks together against too wide displacement or breakage during the drilling and reaming operation even should the

drill and reamer strike solid rock or other obstruction.

Having thus described my invention what I claim as new is,—

1. In a device of the character described, 35 a drill having its main body recessed to form two forks, each fork having a flattened body carrying drilling flanges at either edge of the body of the fork, combined with means connecting the flat bodies of the forks 40 and arranged to limit the expansion of the two forks during the reaming operation.

2. In a device of the character described, a drill having its main body recessed to form two diverging forks, each fork having a 45 flattened body the edges of which are provided with curved flanges, the body of one fork riding on the body of the other fork and a pin and slot connection between the flat bodies of the forks and arranged to 50 limit the movement of said bodies on each other.

In testimony whereof I have signed my name to this specification in the presence of two subscribing witnesses.

WILLIAM M. WALKER.
